UNITED STATES PATENT OFFICE.

THOMAS A. MORRIS, OF ST. PAUL, MINNESOTA, ASSIGNOR, BY MESNE ASSIGNMENTS, TO INTERNATIONAL HARVESTER COMPANY OF NEW JERSEY, A CORPORATION OF NEW JERSEY.

FIBER-TREATING MACHINE.

1,221,358.

Specification of Letters Patent.

Patented Apr. 3, 1917.

Application filed October 31, 1913. Serial No. 798,450.

To all whom it may concern:

Be it known that I, THOMAS A. MORRIS, a citizen of the United States, residing at St. Paul, in the county of Ramsey and State 5 of Minnesota, have invented certain new and useful Improvements in Fiber-Treating Machines, of which the following is a full, clear, and exact specification.

This invention relates to fiber treating 10 machines, and more particularly to means for guiding and feeding into such machines material to be treated therein.

In the manufacture of twine, fiber or material out of which twine is made, has to 15 be treated in various ways before such fiber or material is actually spun into twine. The length of the fiber varies; some is long and some short. Among other things, the rough fiber is passed through machines for 20 combing and spreading purposes. Unless some special precaution is taken the intermixed pieces of fiber are apt, due to the short pieces, to pull apart while being fed into these machines, thereby interrupting 25 the process. Such interrupted feeding is undesirable for many commercial reasons.

It is, therefore, the main object of this 30 invention to automatically guide and feed fiber uninterruptedly into fiber treating machines.

Another object is to provide means for drawing fiber from its source of supply and controlling the feeding movement of the same into fiber treating machines.

These objects are accomplished by properly 35 locating a properly designed lifting drum which automatically draws the fiber from a suitable source of supply without tearing apart the intermixed pieces of fiber 40 in the process, and then directs such fiber onto a suitable conveyer of the machine from which it passes further to be treated.

The invention is illustrated on the accompanying sheet of drawings, in which—

45 Figure 1 is a fragmentary plan view of a fiber treating machine embodying my invention;

Fig. 2 is a side elevation of the same;

Fig. 3 is a longitudinal sectional view of 50 a drum which draws the fiber from any suitable source of supply and directs the feeding movement of the fiber; and

Fig. 4 is an end view of the same feeding drum.

55 The various novel features of my inven-

tion will be apparent from the description and drawings, and will be particularly pointed out in the appended claims.

This fiber treating machine 10 is provided with a conveyer band 11, which passes 60 around two drums 12 and 13, the former being mounted directly upon a shaft 14, upon one end of which is mounted a pulley 15 for receiving a driving motion from any suitable source. These drums, upon which 65 the conveyer band 11 is mounted, are supported by a frame 16 having side members 17 to prevent twine carried on the conveyer from falling off the same. Mounted upon one end of the frame 16, adjacent roller 13 70 of conveyer 11, is a drum 18 having a cylindrical portion 19 which is provided with corrugations 20 and beveled end pieces 21. The cylindrical and end portions of the drum are supported by suitable spiders 22 75 which are keyed to the shaft 23 of drum 18, and upon one end of this shaft 23 is mounted a sprocket wheel 24, around which passes a chain 25, the chain also passing around another sprocket wheel 26 mounted 80 upon one end of shaft 14, from which the chain is driven to transmit motion to the lifting and guiding drum 18. This drum 18 automatically lifts the fiber from any suitable source, such as receptacles 28 85 located at various angles with respect to the longitudinal medial line of the conveyer 11, after the fiber has once been started over the drum and passed onto the conveyer 11. The corrugated parts of the drum assist materially in lifting the fiber. At the same time the drum lifts the fiber in such a manner as to prevent any tearing apart of the intermixed fiber due to the short pieces which are found therein. Furthermore, this drum 90 properly controls the feeding movement of the fiber onto the conveyer 11, from which the fiber is fed into other parts of the fiber treating machine. In other words, the strands of fiber which are drawn from the 100 variously positioned receptacles 28 are delivered to the conveyer 11 in parallel relationship through the control action of the beveled end portions 21. After the fiber has once passed over the feeding drum 18 and 105 started onto the conveyer 11, the drawing of the fiber from its source of supply and the feeding of the same through the whole machine is entirely automatic. By means of this lifting and guiding drum 18 the pieces 110

of fiber are prevented from tearing apart while being fed from the receptacle 28, and in this way the automatic feeding is uninterrupted. This drum 18, which is mounted at one end of the frame 16, is supported by arms 30, which are secured to the side frame members 17, the drum being adjacent the conveyer and located in the most suitable place for accomplishing the desired results.

10 It is evident that there may be modifications in the precise form and arrangement as herein disclosed, and it is my intention to cover all such modifications which do not involve a departure from the spirit and 15 scope of my invention as set forth in the following claims.

What I claim as new is:

1. In a fiber treating machine, the com-

bination of a conveyer, and a corrugated drum for drawing fiber from any suitable 20 source, said drum having beveled end portions for guiding the fiber over said drum onto said conveyer.

2. In a fiber treating machine, the combination of a conveyer, and means for drawing strands of fiber from sources located at various angles with respect to the longitudinal medial line of the conveyer and delivering the strands to the conveyer in parallel 25 30 relationship.

In testimony whereof I affix my signature, in the presence of two witnesses.

THOMAS A. MORRIS.
